Filed Nov. 14, 1972, Ser. No. 306,511

Term of patent 14 years

Int. Cl. D12—16

U.S. Cl. D12—183

FIG. 2

FIG. 1 is a perspective view of an automobile window showing my new design, it being understood that the broken line showing of the automobile is for illustrative purposes only; and

FIG. 2 is an enlarged fragmentary plan view of the fade-out pattern, which pattern extends around the periphery of the window as indicated by stippling in FIG. 1.

I claim:

The ornamental design for an automobile window, as shown and described.
